UNITED STATES PATENT OFFICE.

JOHN H. SHELLEY, OF NEW YORK, N. Y.

CHAIN-MANIPULATING TOOL.

942,356.

Specification of Letters Patent.

Patented Dec. 7, 1909.

Application filed February 17, 1909. Serial No. 478,425.

To all whom it may concern:

Be it known that I, JOHN H. SHELLEY, a citizen of the United States, and resident of New York, in the county and State of New 5 York, have invented certain new and useful Improvements in Chain-Manipulating Tools, of which the following is a specification.

My invention relates to chain manipulating tools and its novelty consists in the construction and adaptation of the parts, as will 10 be more fully hereinafter pointed out.

In the drawings, Figure 1 is a side view of the tool assembled, a portion of each handle being omitted; Fig. 2 is a perspective of the 15 same parts disassembled; Fig. 3 is a section on the plane of the line 3—3 in Fig. 2; Fig. 4 is a perspective of the assembled jaws illustrating their use as a link opening tool, and Fig. 5 is a side elevation of the same parts 20 showing their use as a link-closing tool.

In the drawings, 1 is one handle of the tool, curved at 2 where it is jointed to the other handle provided with an aperture 3 to receive a connecting rivet 4 and expanded 25 laterally at 5 to form a wedge shaped jaw 6 terminating in a beveled edge 7 and provided with a shallow depression 8 on its inner side. A shoulder 9, coöperating in the usual manner with a similar shoulder on the 30 other handle, serves to limit the extent of movement of the handles with respect to each other.

10 is the second handle of the tool curved at 11 where it is jointed to the handle 1, provided with an aperture 12 to receive the connecting rivet 4 and expanded laterally at 13 to form a shoulder adapted to coöperate with the shoulder 9 of the handle 1. It is then continued in the same direction at 15 and 40 turned at substantially a right angle and gradually restricted to form a thick wedge shaped jaw 16 having a slightly concaved surface 17 near its end and terminating in a chisel edge 18. A hammer head 19 is secured 45 to or made integral with this jaw, being placed on its outer side.

The purpose for which the tool is designed mainly to be used is to open and close the chains used to encircle the elastic tires of 50 automobiles. Its use as a chain-opening tool is illustrated in Fig. 4. Such a chain indicated at 20 is provided with one or more long

links 21. This link 21 is arranged as shown in the figure with its reverted portion resting on the inner surface of the jaw 6, the depression 8 serving to prevent any lateral displacement of the link with respect to the jaw when the link is in the position shown. When this link is so placed its free ends 22 are in a line substantially perpendicular with the inner surface of the jaw 6 and the parts are so arranged that the extremity 18 of the jaw 16, if introduced between such free ends 22 and the main body of the link 21 and the jaws are brought toward each other by pressing the 60 handles 1 and 10 together, then the wedge of the jaw 16 will force the ends 22 away from the main body 21 of the link, so that the links of the chain can readily be removed therefrom. Its use as a chain-closing device 65 is illustrated in Fig. 5. In this case the flat main portion of the link 21 is placed against the inner surface 8 of the jaw 6, another link of the chain 20 is placed between the body 70 of the link 21 and its free open ends 22 and 75 now when the jaws 6 and 16 are brought together by pressing the handles, the movement of the jaw being substantially at right angles to the surface of the jaw 6, the free ends 22 of the link 21 are pressed inwardly to the 80 position shown in dotted line in Fig. 5 (and in full line in Fig. 4) and the chain is effectively closed.

The jaw 6 is provided with a beveled edge 85 in order that it may be used as a screwdriver or chisel and thus avoid the necessity of carrying either of such tools. The jaw 16 is provided with the hammer head 17 in order to avoid the need of carrying a separate hammer. Both of these combinations 90 have been found useful.

What I claim as new is:—

1. A chain manipulating tool, comprising pivotally connected handles provided at one end with coöperating jaws, one of said jaws 95 having a substantially straight inner face with a shallow depression therein adapted to seat the rear wall of the chain links and prevent lateral displacement thereof, the other jaw being disposed at right angles to 100 said first-mentioned jaw and having a wedge-shaped operating end, substantially as and for the purpose described.

2. A chain manipulating tool, comprising

pivottally connected handles provided on one side of their pivot axis with coöperating jaws, one of said jaws being longitudinally disposed and having a substantially straight inner side provided with a longitudinally elongated and transversely concaved socket, the other jaw being disposed in angular relation to the first jaw and being tapered to

form a wedge, said latter jaw being provided with a concaved inner side.

Witness my hand this 15th day of February 1909, at New York N. Y.

JOHN H. SHELLEY.
